UNITED STATES PATENT OFFICE.

WILLIAM S. BELL, JR., OF BOSTON, MASSACHUSETTS.

DESIGN FOR A PAPER CUFF AND COLLAR.

Specification forming part of Design No. 2,288, dated April 3, 1866.

To all whom it may concern:

Be it known that I, WILLIAM S. BELL, Jr., of Boston, in the county of Suffolk and State of Massachusetts, have invented a new Design for a Paper Cuff or Collar, of which the following is a full, clear, and exact description, reference being had to the accompanying drawings, making part of this specification, in which—

Figure 1 is a perspective view of my paper cuff. Fig. 2 is a perspective view of my paper collar. Fig. 3 is a section on the line $x\ x$ of Fig. 1. Fig. 4 is a section on the line $y\ y$ of Fig. 2.

My invention consists in embossing a paper cuff or collar with a design which shall represent a "tuck" or "plait," thus causing them

to have an ornamental and unique appearance.

In the said drawings, A represents a paper cuff, and B a paper collar, both of which are embossed or stamped so as to leave a number of raised portions, a , in imitation of tucks or plaits, which produce an exceedingly neat and finished appearance.

What I claim as my invention, and desire to secure by Letters Patent, is—

A design representing a tuck or plait embossed on a paper cuff or collar, substantially as shown and described.

W. S. BELL, JR.
